CLAIM

The ornamental design for a razor handle, as shown and described.

DESCRIPTION

FIG. 1 is a rear perspective view of the razor handle;
FIG. 2 is a front perspective view of the razor handle;
FIG. 3 is a top end view of the razor handle;
FIG. 4 is a bottom end view of the razor handle;
FIG. 5 is a rear view of the razor handle;
FIG. 6 is a side view of the razor handle;
FIG. 7 is a front view of the razor handle; and,
FIG. 8 is a perspective view of the razor handle in a holder.
The broken line showing of the holder is for illustrative
purposes only and forms no part of the claimed design.
